R. G. TURNER

SHUTTLE PLACER FOR LOOMS

Filed Oct. 1, 1924

UNITED STATES PATENT OFFICE.

RICHARD GREENLEAF TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

SHUTTLE PLACER FOR LOOMS.

Application filed October 1, 1924. Serial No. 741,034.

This invention relates to improvements in shuttle placers for looms and an object of the invention is to provide a device of this kind which shall be very strong and positive in its placing action but which will move forwardly against comparatively light resistance when engaged by a shuttle too widely misplaced to be moved into the box.

In application Serial No. 496,351 there is shown a shuttle placer roll rotatably mounted on a slide held rearwardly by a strong spring. When a widely misplaced shuttle is presented to the roll the latter will engage the front wall of the shuttle and be moved bodily forward against the spring, but if the shuttle is only slightly misplaced the roll will engage the rounded end of the shuttle and will push the latter into the box by a rolling action. The spring which holds the roll rearwardly must necessarily be of considerable strength to overcome the friction of the shuttle binder against the shuttle as the latter is boxed and I have found that where a shuttle is misplaced widely enough to cause the roll to engage one of the thin walls of the shuttle, the latter is likely to be crushed by the action of the spring.

It is the general object of my present invention to lessen the pressure against a widely misplaced shuttle and in carrying my invention into effect I provide the slide on which the roll is mounted with a comparatively light spring and make provision for a lateral movement of the slide to bring the latter into engagement with a fixed abutment when the roll engages a slightly misplaced shuttle. When the roll engages a widely misplaced shuttle there will be no lateral displacement of the slide and therefore the latter can move past the abutment without engaging the same.

It is a more detailed object of my invention to provide a placer capable of assuming two different positions and remaining normally in one position when not placing and moving to the other position when placing a shuttle.

With these and other objects in view which will appear as the description proceeds, my invention resides in the combination and arrangement of parts hereinafter described and set forth in the claims.

In the accompanying drawings,

Fig. 1 is a top plan view of my improved placer,

Fig. 2 is a diagrammatic view showing the action of the placer when engaged by a widely misplaced shuttle, and

Fig. 3 is a view similar to Fig. 2 but with the placer in engagement with a slightly misplaced shuttle.

Referring to the drawings it will be seen that I have provided a breast beam 10 on which is mounted a stand 11 having a guide-way 12 therein for the side filling stop motion slide 13. A stand 14 extends from the breast beam and has pivoted thereto a knock off lever 15, one end of which is positioned for dislodging the shipper handle 16 from notch 17 formed in the casting 14 to stop the loom. The inner end of lever 15 is made in the form of a cylinder 18 in which is slidably mounted a plunger 19 having an enlarged head 20 projecting beyond the cylinder and held in such position by a coil spring 21. A cotter pin 22 passing through the plunger and engaging the lever limits movement of the head 20.

In carrying out my invention I form the stand 11 with walls 30 and 31, between which is an upstanding guide 32. A slide 33 moves freely between the walls and is held in place by a rod 34 having the ends thereof received in the slide and passing through said guide 32. The rod is held to the slide by a set screw 35.

A head 36 is pivoted as at 37 on the slide 34 and has a forwardly extending tail 38 which permits angular adjustment of the head by means of screws 39 and 40, respectively, which are mounted on the slide. A roll 41 adapted for engagement with the shuttle is rotatably mounted on a pin 42 carried by the head 36. The matter thus far described is substantially the same as set forth in the aforesaid application, Serial No. 496,351.

My invention relates more particularly to making provision for varying the resistance which the placer affords to a misplaced shuttle and I accordingly provide the slide 34 with a shoulder 50, making that portion of the slide immediately in front of the shoulder 50 narrower than the forward end thereof so that the slide may swing through a slight angle about the upstanding guide 32. The rod 34 fits the guide 32 loosely enough

2
to permit such angular motion. The slide is normally held in the position shown in Fig. 1 by means of a spring 51 having a bent end 52 which is positioned for sliding 5 contact with the adjacent edge of the slide and having also a forward end 53 by means of which said spring may be fastened to the frame 11. The shoulder 50 is of slightly less height than the space between the wall 10 30 and the slide 33 at the rear of said wall 30 when the slide is in normal position.

In order to hold the slide 33 in rear position I surround the rod 34 with a light spring 54 the front end of which engages 15 the guide 32 and the rear end of which is in contact with the slide. Plates 55 are secured to the stand by means of the bolts 56 which hold the stand to the breast beam, and said plates extend over the slide 33 and help 20 to prevent upward movement thereof.

Under normal operation the shuttle S will be properly boxed and will move forward beyond the roll 41 without engaging the same, but if the shuttle should be widely misplaced 25 as indicated in Fig. 2 the front wall of the shuttle will engage the roll 41 and the slide 33 will be moved forwardly against the action of light spring 54 and engage plunger 20 to swing the lever 15 to stop the loom. 30 This forward motion will be accompanied by such a light pressure as will not endanger the shuttle. Should the shuttle be slightly misplaced, however, as shown in Fig. 3, it will move the roll 41 to the left against the 35 action of spring 51 because of the fact that said roll will engage the rounded part of the shuttle.

This will bring the shoulder 50 opposite the rear portion of wall 30 so as to prevent 40 forward motion of the slide. The roll 41 is therefore required to move about fixed axis 37 and place the shuttle. It will be noted that the lateral movement to bring the shoulder against a fixed stop occurs only 45 when it is possible to place the shuttle due to the engagement of the rounded end of the latter with the roll. While I have shown the walls 30 and 31 as parallel and the slide 33 tapered, yet I do not wish to be limited 50 to this construction, as it will suffice to employ any arrangement of the parts which will permit the shoulder 50 to move into engaging position with a fixed stop.

From the foregoing it will be seen that I 55 have provided a shuttle placer which is capable of assuming two lateral positions depending upon the extent to which the shuttle is misplaced. If the shuttle is so widely misplaced as to bring a weakened 60 portion thereof opposite the roll the latter will move forwardly against the action of the comparatively light spring 54. If the shuttle be only slightly misplaced so that the rounded end thereof engages the roll the 65 latter will be given a slight lateral displace-

ment which will prevent further forward movement of the roll, thus requiring placing of the shuttle.

Having thus described my invention it will be apparent that changes and modifications may be made therein by those skilled in the art without departing from the spirit and scope of the invention, and I do not wish to be limited to the details herein disclosed, but what I claim is:

1. In a loom, a shuttle placer normally inoperative when the shuttle is properly placed and receiving a shuttle placing movement by engagement with a misplaced shuttle, said placer being movable forwardly with a widely misplaced shuttle, and movable laterally by a slightly misplaced shuttle, and means to arrest forward motion of the placer when moved laterally.

2. In a loom, a shuttle placer normally inoperative when the shuttle is properly placed and receiving a shuttle placing movement by engagement with a misplaced shuttle, said placer being movable to assume two lateral positions, said placer assuming one or the other of said positions depending upon whether the shuttle be slightly or widely misplaced, said placer when in the position corresponding to a slightly misplaced shuttle having a placing action and when in the position corresponding to a widely misplaced shuttle being yieldable without having a placing action.

3. In a loom, a shuttle placer normally inoperative when the shuttle is properly placed and receiving a shuttle placing movement by engagement with a misplaced shuttle, means to hold the placer yieldingly in normal position and permitting lateral movement of the placer when the latter is engaged by a slightly misplaced shuttle, and means to arrest forward movement of the placer when the latter is moved laterally.

4. In a loom, a shuttle placer normally at rest and receiving a shuttle placing movement by engagement with a misplaced shuttle, a slide on which said placer is mounted capable of assuming two positions, relatively light resilient means to resist forward movement of the slide when in one position, and means to positively prevent forward movement of the slide when in the other position.

5. In a loom, a shuttle placer normally at rest and receiving a shuttle placing movement by engagement with a misplaced shuttle, a slide on which said placer is mounted, a guide in which said slide is loosely mounted, said slide being capable of assuming two positions in said guide, means to permit yielding forward movement of the slide when in the other position.

6. In a loom, a shuttle placer normally inoperative when the shuttle is properly placed and having a shuttle placing movement

when engaged by a misplaced shuttle, said shuttle placer being capable of assuming two positions and movable when in one of said positions with a widely misplaced shuttle without placing the latter and held against motion with a slightly misplaced shuttle when in the other position to have a placing movement.

5. In a loom, a shuttle placer normally at rest and having a shuttle placing movement when engaged by a misplaced shuttle, a slide 10 on which said placer is mounted, a guideway for the slide having walls in which said slide is loosely fitted to permit lateral movement of the slide, resilient means acting laterally against the slide to move the latter against one wall of the guideway, and means 15 formed on the slide to engage the other wall of the guideway when the slide is moved laterally against said resilient means to prevent 20 forward movement of the slide in the guideway.

6. In a loom, a shuttle placer normally at rest and having a shuttle placing movement 25 when engaged by a misplaced shuttle, a slide on which said placer is mounted, a guideway for the slide in which the latter is loosely

fitted, yielding means to hold the slide rearwardly, resilient means to hold said slide normally against one side of the guideway 30 and permitting movement of the slide on the other side of the guideway to allow the slide to assume two lateral positions, a shoulder formed on the slide normally movable in a path out of alignment with one side of the guideway and movable into alignment with 35 said last named side of the guideway when the slide moves to the other position to arrest forward movement of the slide.

7. In a loom, a shuttle placer normally at rest and having a shuttle placing movement when engaged by a misplaced shuttle, a slide 40 on which said placer is mounted, a guide for said slide permitting the latter to assume two positions, and co-acting abutments formed 45 on the slide and the guide, said abutments being out of alignment when the slide is in one position to permit the same to move forwardly and being in engaging position when the slide is in the other position to prevent 50 the slide from moving forwardly.

In testimony whereof I have hereunto affixed my signature.

RICHARD GREENLEAF TURNER.
